UNITED STATES PATENT OFFICE.

JOSEPH G. MOORE, OF CLEVELAND, OHIO.

INTERLOCKING BLOCK AND ORDER SIGNAL.

No. 838,262.

Specification of Letters Patent.

Patented Dec. 11, 1906.

Application filed July 25, 1906. Serial No. 327,663.

To all whom it may concern:

Be it known that I, JOSEPH G. MOORE, a citizen of the United States, residing at Cleveland, in the county of Cuyahoga and State of Ohio, have invented a certain new and useful Improvement in Interlocking Block and Order Signals, of which the following is a full, clear, and exact description.

The object of the present invention is to provide a mechanism for setting train-order signals and block-signals to obtain certain advantages, which will appear more fully below.

The operation and purpose of block-signals are well known, the purpose of block-signals being to prevent the train from moving onto an occupied block, and when this signal is set the train must come to a stop and not proceed until the signal is changed.

In the operation of trains it is frequently necessary for the agent to give the engineers or conductor of the train an order for the government of the immediate future conduct of the train. There are two classes of train-orders, one of which simply requires the train to slow down, so that the order may be handed to the conductor as he passes the station, and the presence of this type of train-order at the station is ordinarily indicated

to the engineer by having a green signal, either a flag or lantern, displayed in any suitable place, ordinarily on the block-signal mast. The other type of train-order requires the train to come to a full stop, so that the order may be read to the trainmen by the agent and the signatures of the trainmen obtained to the order, and the fact that such an order is to be delivered is usually indicated by displaying a red signal, either flag or lantern. Such orders are not ordinarily given unless the conditions are such that the block-signal is set so as to warn the train not to proceed onto the next block.

It is the purpose of the present invention to provide an easy means by which the station agent may, without leaving his telegraph instrument, set the train-order signals, as well as the block-signal. Now it is desirable to provide some means when the red train-order signal, which requires the train to come to a full stop, is set that this particular class of train-order should be delivered without fail, as it is usually of considerable importance. As a matter of fact, the engineers sometimes overlook the train-order signals if they note that the block-

signal is down, indicating that the block is clear ahead of them, as they then feel that they can proceed without danger. Furthermore, it frequently happens that when the station agent has set a red train-order signal and also has the block-signal set word comes over the wire that the block is clear, and the agent, from sheer force of habit, involuntarily reaches for the lever which withdraws the signal, thus indicating to the engineers that the block is clear, and it frequently happens that the engineers then overlook the order-signal and proceed onto the next block without stopping for the orders, whereas if the block-signal had remained set they would have come to a full stop and the agent would have been enabled to deliver the orders.

It is my purpose to provide means whereby the agent may, without leaving his office, set both the block and the train-order signals and by which when the block-signal and the train-order signal requiring the train to come to a full stop are each set the block-signal is locked in position and may not be involuntarily released by the operator or released at all until the train-order signal is released.

Referring to the accompanying drawings, which illustrate an embodiment of my invention, Figure 1 is a side elevation showing the portion of the parts when all signals are down. Fig. 2 is a perspective view, and Fig. 3 is a sectional view, illustrating the connection between the hand-lever and the connecting-rods for the train-order signals. Figs. 4, 5, and 6 are views similar to Figs. 1, 2, and 3, but showing the parts in the position in which the block-signal and the red train-order signal are set. Fig. 7 is a detail perspective view of the mechanism which operates the train-order target-plate.

In the various figures it will be seen that I have secured to the same semaphore-mast A a block-signal semaphore B of the ordinary type and two train-order signals, a green C¹ and a red C², together with a target-plate C³, having red and green lenses therein. For the purpose of operating the block-signal semaphore I provide a series of connecting-rods B' B² B³ and a hand-lever B⁴, suitably mounted. The two train-order signals are each operated by a single hand-lever C⁴, operating through two separate sets of connecting-rods.

Each of the train-order signal-flags C¹ C² is hung on an arm, which arms are pivotally

mounted at their inner end upon a short shaft A', projecting from the semaphore-mast, upon which shaft is also pivotally mounted the target-plate C³, having the red and green lenses corresponding to the red and green flags, which target-plate is operated, together with the flags, after a manner to be pointed out below. One of the flags—for example, the green flag C'—has pivotally attached 5 near the inner end of its arm a connecting-rod C¹¹, which through a bell-crank C¹² at the lower portion of the mast receives motion from a second connecting-rod C¹³, having a slotted end. The hand-lever C⁴ for operating 10 the train-order signals has projecting therefrom a pin C⁷, passing through the slot on the second connecting-rod C¹³. The weight of the flag C' and its arm are ordinarily sufficient to throw the slotted connecting-rod C¹³ back toward the operating-lever 15 to such position that the forward end of the slot is adjacent to the pin C⁷ projecting from the hand-lever, when the hand-lever is in its intermediate position, as shown in Fig. 1. 20 Thus the forward movement of the hand-lever C⁴ will immediately transmit motion through the connecting-rods C¹³ and C¹¹ and bell-crank C¹² to the green signal-flag C' and cause it to be thrown upward, though it is 25 plain that a movement of the hand-lever C⁴ from the intermediate position in the opposite or rearward direction would be without effect upon the green signal-flag, as the pin C⁷, projecting from the hand-lever, would merely 30 ride along the slot at the end of the connecting-rod C¹³.

The red flag C² has near the inner end of its arm a slotted projection C²¹, and adjacent thereto is a short link C²², to which is pinned 40 a connecting-rod C²³, which through the medium of a second bell-crank C²⁴ at the lower end of the semaphore-mast receives motion from still another connecting-rod C²⁵, which has a slotted end and is operated by the same 45 hand-lever C⁴ which operates the green flag C'. The pin connecting the before-mentioned short link C²² and its connecting-rod C²³ passes through the slotted projection C²¹ near the inner end of the flag-arm. This arrangement allows the link C²² to move upward a short distance before the flag itself is caused to move, this being for the purpose of obtaining the correct relative position of the target-plate, as will appear below.

55 The slotted connecting-rod C²⁵ for operating the red flag is itself operated by the same pin projecting from the hand-lever C⁴, which operates the connecting-rod of the green flag and will by arrangement of the bell-crank, as 60 shown, be drawn forward by the weight of the flag, so that the rear end of the slot is near the pin of the hand-lever when the latter is in its intermediate position. Thus a rearward movement of the hand-lever will cause 65 the elevation of the red flag, while the for-

ward movement of the lever will not affect the latter, since in such a movement the projecting pin will merely ride along the slot.

From the above it will be plain that the movement of the hand-lever in one direction 70 will throw up the green signal without interfering with the red, and a movement from the intermediate position in the opposite direction will similarly set the red flag without interfering with the green, allowing the latter 75 to remain at rest.

For the purpose of causing the target-plate carrying the lenses to move a proper distance to show the lens corresponding with the flag I provide the target-plate with a 80 projecting pin C³¹, which lies in the path of movement of the green-flag arm and the short link which operates the red flag, each of which has therein a small hooked portion to catch the pin and carry it upward. (See 85 Fig. 7.) Obviously in order to carry the target-plate farther when it is thrown by one flag than by the other it will be necessary to have one of these hooks somewhat in advance of the other, and it is in order to secure the 90 proper relative spacing of these movements that I have provided the slot in the arm at the end of the red flag, which allows the short link C²² to move and start the target-plate upward a short distance before the red 95 flag C² itself is lifted. This detail feature, however, is capable of the widest sort of variation, and while I have used the form here shown in some of my structures I do not use it in all cases.

100 Fixed to the hand-lever C⁴, which operates the order-signals, and projecting rearwardly therefrom is a bar C⁵, which I have shown as mounted at its rear end upon the pivot of the hand-lever B⁴, which controls the block-signal 105 semaphore. The exact place of mounting the rear end of this bar is not material, however. The upper face of the bar has a cam-surface C⁶, on which rides one end of a lock-bar D, pivoted to the stand of the semaphore-lever. This lock-bar has a notch D' on its under side adapted to fit over a short pin B⁵, projecting from the semaphore-lever when the latter is in its forward position, at which the block-signal is "set" indicating a 110 closed track. The cam-bar C⁵, however, movable with and controlled by the train-order lever, is so shaped as to hold the lock-bar D up and prevent the notch D' from falling over the pin B⁵ on the semaphore-lever 115 B⁴ even when the latter is in its forward position, unless at the same time the train-order lever C⁴ be thrown back in such manner as to set the red train-order signal C². In this last event the cam-bar will allow the lock-bar to 120 drop, so that the pin B⁵ on the semaphore-lever will be caught in the notch of the lock-bar and it will be impossible to throw the 125 semaphore-lever B⁴ back until the red train-order signal C² is released. This automatic 130

locking of the block-semaphore will take place whether it first be set and the red train-order signal then be set or the red train-order signal first be set and the block-semaphore then be set. It is not material in which order the action takes place. The result will always be that once the block-semaphore and the red train-order signal are both set it will be impossible to release the block-semaphore until the red train-order signal is released. Thus no involuntary or careless action on the part of the station-agent will open up the block and present the opportunity for the engineer to overlook the special orders which he must stop and receive.

In the foregoing description I have referred to the order-signals by their conventional colors; but of course it is understood that this is merely for convenience, as special conditions might require the use of different colors. Further, the detail mechanism for operating the various movable parts has been selected from a single embodiment of my invention; but there are many variations in detail which it is possible to introduce not in any way affecting the general principle involved.

Having thus described my invention, I claim—

1. In combination a block-signal and operating mechanism therefor, an order-signal and operating mechanism therefor, and means controlled by the operating mechanism of the order-signal adapted to lock said block-signal when the latter is set.

2. In combination a block-signal and oper-

ating mechanism therefor, a plurality of order-signals and operating mechanism therefor and locking means for the block-signal operable by the movement of the mechanism in setting one of the order-signals.

3. In combination a block-signal and operating mechanism therefor, a plurality of order-signals and operating mechanism therefor, and locking means for the block-signal operable by the movement of the mechanism in setting one of the order-signals and independent of the movement of the mechanism in setting the other order-signals.

4. In combination, a block-signal and operating mechanism therefor, an order-signal and operating mechanism therefor, the order-signal and its operating mechanism being freely movable with regard to the block-signal, the block-signal being freely movable with regard to the order-signal when the latter is not set, and locking means adapted to lock the block-signal in set position when the order-signal is set.

5. In combination a block-signal and mechanism for setting the same, a train-order signal and mechanism for setting the same, and means whereby the said first signal may be locked in set position only when the said second signal is in set position.

In testimony whereof I hereunto affix my signature in the presence of two witnesses.

JOSEPH G. MOORE.
